UNITED STATES PATENT OFFICE.

WILLIAM PATERSON, OF SCHENECTADY, NEW YORK.

AUTOMATIC SPRING-TENSION FEED.

No. 926,508

Specification of Letters Patent. Patented June 29, 1909.

Application filed December 22, 1908. Serial No. 468,863.

To all whom it may concern:

Be it known that I, WILLIAM PATERSON, a citizen of the United States, residing at Schenectady, in the county of Schenectady,

5 State of New York, have invented certain new and useful Improvements in Automatic Spring-Tension Feeds for Flat-Bed Web-Perfecting Printing-Presses, of which the following is a specification.

10 My invention relates to improvements in automatic spring tension feeds for flat bed web perfecting printing presses and the object of my invention is to provide simple and effective means of regulating the feed of 15 paper in the press.

I attain this object by the mechanism illustrated in the accompanying drawings, in which—

20 Figure 1 is a perspective view of a section of a printing press showing my automatic feed device in position; and Fig. 2 is a perspective view of a complete arm and fork showing means of securing spring tension on feed roller.

25 In the drawings like letters of reference indicate corresponding parts in each figure.

I provide a series of arms secured by means of set screws to a transverse shaft and hinged at the ends of these arms are a series 30 of forks designed to keep the feed rollers in close contact with the calender roller over which the paper passes. It is necessary that the paper be held perfectly taut as otherwise it would buckle and tear.

35 My invention keeps an automatically regulated strain on the paper and eliminates the expensive and unreliable arrangement of steel shafts and leather belts now in general use.

40 Referring to the drawings, A is the main frame of the printing press, B is the calender roller over which the paper C passes.

D is a transverse steel shaft supporting the arm E which is secured by means of a set screw *a*.

45 F is a fork hinged to the arm E at *b* and retaining the roller G in position.

H is a tension spring secured at one end to an extending lug *c* on the fork F and at the other end to a tension screw *d*. The tension 50 screw *d* is secured by the depending lug *e* on the arm E and is provided with a thumb nut *f*.

55 It will be readily seen that as the thumb nut *f* is screwed up, the tension on the spring is increased. This permits a quick adjustment and assures a constant pressure of the feed rollers G on the calender roller B.

What I claim as new and desire to secure by Letters Patent of the United States, is:—

60 1. In an automatic spring tension feed, the combination of a shaft, a series of arms adjustably mounted on said shaft, hinged rollers mounted on said arms, springs forming part of the tension feed and movable 65 with said rolls during adjustment on said shaft, and means for varying the tension of the springs to change the pressure of the rollers.

2. In an automatic spring tension feed, 70 the combination of a shaft, a series of supporting arms mounted thereon, means for adjusting the arms on the shaft, hinged forks on said arms, rollers carried on said forks, springs for the hinged forks, and 75 means for varying the tension of said springs to change the pressure of the rollers.

In witness whereof, I have hereunto set my hand this 12th day of March, 1909.

WILLIAM PATERSON.
